TELEVISION PICTURE TUBE SCREEN

Louis Malter, Newark, N. J., assignor to Radio Corporation of America, a corporation of Delaware

Application November 30, 1940, Serial No. 367,877

5 Claims. (Cl. 250—164)

This invention relates to television systems of the type employing cathode ray tubes and more particularly to picture screens for kinescope tubes.

In television receiving picture tubes a decrease in detail is encountered due to the halation caused by the electron beam striking the screen of fluorescent material. Halation involves the spreading of light beyond its proper boundaries.

One of the principal causes of halation in a kinescope screen is the reflection of the light from the fluorescent material between the surfaces of the member supporting the fluorescent material. When the fluorescent material is coated on the supporting member, light from the fluorescent material is permitted to enter the supporting member at the inner surface over a wide angle and hence be reflected from both surfaces to a comparatively high degree.

This reflection can be reduced considerably by decreasing the optical contact between the supporting member and the screen material. If no optical contact existed between the screen material and the transparent supporting member, none of the light which enters the supporting member on the surface of the supporting member adjacent the fluorescent material can experience total reflection at the opposite surface of the supporting member.

It is practically impossible to reduce the optical contact between the supporting member and screen material sufficiently without experiencing the trouble from the screen material dropping off the supporting member.

According to this invention, the optical contact between the screen material and the supporting member can be effectively reduced without decreasing the mechanical support of the screen material. A layer of small transparent particles of glass or quartz is interposed between the screen material and the supporting member. Therefore, the only effective contact between the fluorescent material and the supporting member is that comparatively small area of contact between the layer of particles and the supporting member.

The primary object of this invention is to provide a picture screen for a kinescope.

Another object of this invention is to provide a means for reducing halation in kinescopes.

Other and incidental objects of the invention will be apparent to those skilled in the art from the following specification considered in connection with the accompanying drawing, in which

Figure 1 is a sectional view of a kinescope,

Figure 2 is a greatly enlarged cross section of a screen in accordance with one form of this invention, and

Figure 3 is an enlarged cross section of another form of this invention.

Referring in more detail to Fig. 1, there is an envelope 1 containing an electron gun with an indirectly heated cathode 3, a control electrode 5, a first anode 7, and a second anode 9. The electron gun is adapted to produce an electron beam which is deflected by the horizontal deflecting coils 11 and the vertical deflecting coils 13 across the image screen 15, the detail of which is shown more fully in Figs. 2 and 3.

Fig. 2 shows a supporting member 17 which may be the end of the envelope 1 of Fig. 1 or it may be a supporting member positioned inside the envelope 1 of Fig. 1 upon which there is a layer of small transparent particles 19 which may be of small polished spheroidal glass or quartz beads. The spheroidal particles may be made adherent to the supporting member 17 by the use of a suitable binder or by actually bringing about a slight sintering action at the points of contact between the particles 19 and the supporting member 17 under the influence of heat.

It will be noticed that only a small fraction of the supporting member 17 is in actual physical contact with the spheroidal particles 19. The particles are brought into as close physical contact with each other as is practically possible. A coating of fluorescent material 21 is then spread over the surface of the particles.

In operation, light from the screen material 21 enters the spheroidal particles from the back side. Due to the close physical or optical contact between the fluorescent material 21 and the particles 19, light travels in all directions within the particles 19 and is either transmitted through the particles 19 after suffering refraction, or is reflected until either scattered at the surface of contact between the fluorescent material 21 and the spheroidal particles 19 or transmitted into the supporting member at the point of contact between it and the spheroidal particles 19.

The light which is transmitted through the spheroidal particles 19 in an upward direction will enter the supporting member 17 and will be transmitted without experiencing total reflection, because of the relatively small angle from perpendicular that the light intersects the surfaces of the supporting member 17.

Thus, the only upwardly moving light which might experience a total reflection is that which is transmitted through the points of contact be-

tween the spheroidal particles 19 and that light which intersects the supporting member 17 at angles greater than the critical angle. Since the area of the point of contact between the particles 19 and the supporting member 17 is only a small fraction of the total surface of the supporting member 17, a marked diminution of the amount of light suffering total reflection in the supporting member 17 is brought about.

Halation will be further reduced by reason of the fact that light which experiences total reflection at the outer surface of the supporting member 17 would normally suffer total reflection again at the lower surface unless it impinges upon a region of optical contact with some other particle or object. In the conventional structure, the optical points of contact between the fluorescent material particles and the bulb serve as points for diffused reflection of the totally reflected rays. It is the upwardly directed portion of the diffused reflected rays which result in halation with its consequent reduction of detail and contrast.

Since, in accordance with this invention, only a small fraction of the supporting member 17 is in contact with the spheroidal particles 19, most of the light totally reflected from the upper surface of the supporting member 17 will be totally reflected again from the lower surface. This process of reflection will repeat itself with ultimate absorption of the totally reflected rays.

Fig. 3 shows another form of this invention in which the supporting member 23 has thereon a layer of irregularly shaped particles 25 whose optical contact with the supporting member 23 covers a very small relative part of the lower surface of the supporting member 23. The layer of fluorescent material 27 covers the lower surface of the mosaic particles 25. The operation of this form of the invention is similar to that given above for the form of the invention shown in Fig. 2. The light caused by the impinging of the electron beam upon the fluorescent material 27 is caused to reflect in the particles 25 until it is projected into the supporting member 23 through its point of contact with the particles 25.

While several systems for carrying this invention into effect have been indicated in this drawing, it will be apparent to one skilled in the art that this invention is by no means limited to the particular organization shown and described but that many modifications may be made without

departing from the scope of this invention as set forth in the appended claims.

I claim as my invention:

1. In a picture-reproducing system including an envelope and means positioned in said envelope for producing an electron beam, a mosaic positioned in the path of said electron beam and comprising spheroidal transparent particles having a coating of fluorescent material on the surface adjacent said electron gun.
2. In a picture-reproducing system including an envelope and means positioned in said envelope for producing an electron beam, an image screen positioned in the path of said electron beam and comprising a mosaic of transparent particles having a coating thereon of fluorescent material, a transparent member mounted in one end of said envelope upon which said particles are supported with substantially none of said fluorescent material in contact therewith.
3. In a picture-reproducing system including an envelope and means positioned in said envelope for producing an electron beam, an image screen positioned in the path of said electron beam and comprising a mosaic of spheroidal transparent particles on one end of said envelope and said particles having a coating thereon of fluorescent material.
4. In a picture-reproducing system including an envelope and means positioned in said envelope for producing an electron beam, an image screen positioned in the path of said electron beam and comprising a mosaic of transparent particles having a coating thereon of fluorescent material, a transparent member mounted in one end of said envelope upon which said particles are adapted to be supported, the total of the area of contact between the particles and said member being substantially less than the area of said mosaic.
5. In a picture-reproducing system including an envelope and means positioned in said envelope for producing an electron beam, an image screen positioned in the path of said electron beam and comprising a mosaic of spheroidal transparent particles on one end of said envelope and said particles having a coating thereon of fluorescent material, the total of the area of contact between the particles and envelope being substantially less than the area of said mosaic.

LOUIS MALTER.
